DESIGN FOR A POST HOLE DIGGING ATTACHMENT

Marshall S. Anderson, Denver, Colo., assignor to
McCarty-Sherman Distributing Corporation,
Denver, Colo., a corporation of Colorado

Application August 26, 1942, Serial No. 108,043

Term of patent 7 years

To all whom it may concern:

Be it known that I, Marshall S. Anderson, a citizen of the United States, residing at Denver, in the county of Denver, State of Colorado, have invented a new, original, and ornamental Design for a Post Hole Digging Attachment, of which the following is a specification, reference being had to the accompanying drawings, forming a part thereof.

Fig. 1 is a top plan view of a post hole digging attachment showing my new design.

Fig. 2 is a rear elevational view thereof and
Fig. 3 is a side elevational view thereof.

The portions shown in broken lines are for
illustrative purposes only.

I claim:

The ornamental design for a post hole digging attachment, as shown and described.

MARSHALL S. ANDERSON.
